(57) **CLAIM**

The ornamental design for a release liner structure carrying
a face mask seal, as shown and described.

DESCRIPTION

FIG. 1 is a top, left perspective view of a release liner
structure carrying a face mask seal depicting our new
design;

FIG. 2 is a front view of the release liner structure carrying
a face mask seal depicted in FIG. 1;

FIG. 3 is a rear view of the release liner structure carrying
a face mask seal depicted in FIG. 1;

FIG. 4 is a left side elevation view of the release liner
structure carrying a face mask seal depicted in FIG. 1;

FIG. 5 is a right side elevation view of the release liner
structure carrying a face mask seal depicted in FIG. 1;

FIG. 6 is a top plan view of the release liner structure
carrying a face mask seal depicted in FIG. 1;

FIG. 7 is a bottom plan view of the release liner structure
carrying a face mask seal depicted in FIG. 1;

FIG. 8 is an exploded view of the release liner structure
carrying a face mask seal depicted in FIG. 1, from a bottom,
right perspective view; and,

FIG. 9 is a bottom, right perspective view of the face mask
